[57] CLAIM

The ornamental design for a bow sight, substantially as shown and described.

DESCRIPTION

FIG. 1 is a perspective view as seen from one side and above the bow sight of my new design.

FIG. 2 is a perspective view as seen from an opposite side of my design from that of the view of FIG. 1.

FIG. 3 is a bottom plan view of my design.

FIG. 4 is an elevational view of my design as seen from a front end of my design.

FIG. 5 is an elevational view as seen from a rear end of my design.

FIG. 6 is a side elevational view thereof, the bow being shown in broken lines for illustrative purposes only and forms no part of the claimed design.

FIG. 2
